CALVIN B. PATCH, OF GLENELLYN, ILLINOIS, ASSIGNOR TO WILLIAM H. MINER, OF CHAZY, NEW YORK.

FRICITION-GEAR FOR LOCOMOTIVES.

1,251,094.

Specification of Letters Patent. Patented Dec. 25, 1917.

Application filed November 6, 1915. Serial No. 59,910.

To all whom it may concern:

Be it known that I, CALVIN B. PATCH, a citizen of the United States, residing at Glenellyn, in the county of Du Page and 5 State of Illinois, have invented a certain new and useful Improvement in Friction-Gears for Locomotives, of which the following is a full, clear, concise, and exact description, reference being had to the accompanying 10 drawings, forming a part of this specification.

This invention relates to improvements in friction gears for locomotives.

An object of the invention is to provide 15 a gear of heavy capacity and having a graduated action, and which is more particularly adapted for application to the front ends of locomotives.

In said drawing, Figure 1 is a horizontal, 20 sectional view of a portion of a locomotive showing my improvement in connection therewith, and Fig. 2 is a longitudinal, vertical sectional view taken substantially on the line 2—2 of Fig. 1.

25 In said drawing, 10 denotes a casting at the front end of the locomotive, the same being provided with a substantially rectangular opening or pocket 11 within which is adapted to be received the improved gear.

30 As shown, the gear proper consists of a casting A having two friction cylinders 12—12 at the sides thereof, two spring casings 13—13, one for each friction cylinder, and a centrally located preliminary spring 35 chamber 14. As is apparent from the drawing, each combined friction cylinder and spring casing 12—13 is closed at the front end by a wall 15 and open at the rear end, whereas the spring chamber 14 is closed at

40 its rear end by an integral wall 16 and open at its front end. All the foregoing friction shells and spring chambers are cast integrally. Within each friction shell 12 is mounted the friction mechanism consisting 45 of friction shoes 17 and wedge 18 and within each spring chamber 13 is a heavy spring 19 which preferably consists of two nested coils. The elements of each friction mechanism are held in suitable assembled relation

50 by means of a retaining bolt 20. Within the spring chamber 14 is a relatively heavy preliminary spring 21 which bears at its rear end against the wall 16, and at its front end against a spring follower 22 which is telescoped within the spring chamber 14 and is

limited in its inward movement by an annular shoulder 23. The preliminary spring and spring follower 22 are held in assembled relation by means of a bolt 24. The wedges 18 of the friction mechanisms bear against 60 a heavy rear follower 124 which is prevented from rearward movement by the rear wall 25 of the casting 10. Forward movement of the casting A is prevented by the removable keys 26 which are inserted through suitable 65 openings in the upper and lower walls 27 and 28 of the casting 10. The draw bar 29 bears at its inner end against the spring follower 22 and is connected by a key 30 with a yoke 31, which encircles the casting A and 70 the follower 124, the rear end of said yoke being accommodated in a recess 32 at the back of the pocket 11.

Upon inward or buffering movement of the draw-bar 29, the preliminary spring 21 is 75 first compressed until the follower 22 engages the shoulder 23. Thereafter, the entire casting A is moved rearwardly thus actuating the twin arranged friction mechanisms. In draft or forward movement of 80 the draw-bar 29, the rear follower 124 is pulled by the yoke thereby actuating the two sets of friction mechanisms since the casting A is held by the key stops 26—26. As clearly appears from Fig. 2, rearward movement of the coupler key 30 is permitted without moving the yoke 31 by the elongated slots 33 in the yoke arms. 85

From the preceding description and drawing, it will be noted that the draw-bar is 90 movable between the two laterally spaced friction shells and spring casings thereby obtaining a relatively short overall length of the gear, in the center line of draft. Also, it is apparent that the action under buff is 95 graduated and an ultimate high capacity is obtained.

I claim:

1. In mechanism of the character described, the combination with twin arranged, 100 laterally spaced friction mechanisms adapted to have a draw-bar move therebetween, of a spring independent of the friction mechanisms operable by the draw-bar.

2. As an article of manufacture, a casting 105 for shock absorbing mechanism, said casting having twin arranged, laterally spaced friction shells, both open at the same end, and a spring chamber intermediate said shells, said spring chamber being open at one end. 110

3. In mechanism of the character described, the combination with spaced, twin arranged friction mechanisms, of a preliminary spring located between said friction mechanisms, a draw-bar for operating said preliminary spring upon buffing movement, said friction mechanisms being operated simultaneously on draft and independently of the preliminary spring.
- 10 4. In mechanism of the character described, the combination with a rear follower, a casting in front of said follower, said casting having twin arranged friction shells opening toward the rear and a spring chamber intermediate said shells opening toward the front, friction elements coöperat-

ing with each of said shells and resisted in rearward movement by said rear follower, and main springs associated with each of said friction mechanisms, of a preliminary 20 spring within said spring chamber, a spring follower in said preliminary spring chamber and means for limiting the inward movement of said spring follower under buff, the friction shells being moved rearwardly 25 through the instrumentality of said spring follower after the preliminary spring has been compressed.

In witness that I claim the foregoing I have hereunto subscribed my name this 18th 30 day of October, 1915.

CALVIN B. PATCH.
